UNITED STATES PATENT OFFICE.

BUANAFEDE MONTERASTELLI, OF PASSAIC, NEW JERSEY, ASSIGNOR OF ONE-FOURTH
TO EDWARD MURRAY, OF PASSAIC, NEW JERSEY.

AUTOMATIC STOP FOR RAILWAY-TRAINS.

1,103,368.

Specification of Letters Patent. Patented July 14, 1914.

Application filed December 6, 1913. Serial No. 805,089.

To all whom it may concern:

Be it known that I, BUANAFEDE MONTERASTELLI, a citizen of the United States, residing at Passaic, in the county of Passaic 5 and State of New Jersey, have invented certain new and useful Improvements in Automatic Stops for Railway-Trains, of which the following is a specification, reference being had to the accompanying drawings.

10 This invention relates to new and useful improvements in stopping devices for railroad trains, and more particularly to an automatic stop therefor, and the primary object of the invention is to provide a device 15 of this character which will positively stop the train at predetermined points to prevent accident in case of inadvertence on the part of the engineer.

15 A further object of the invention resides 20 in providing an improved stop which, when actuated, will be retained in such position until such time as released by manual operation.

25 Still another object of the invention resides in providing a device which is simple and durable in construction, inexpensive to manufacture and one which will be very efficient and useful in operation.

30 With these and other objects in view, the invention consists in the novel features of construction, combination and arrangement of parts as will be hereinafter referred to and more particularly pointed out in the specification and claims.

35 In the accompanying drawings forming a part of this application, Figure 1 is a rear elevation of an improved stop mechanism constructed in accordance with my invention, showing the same applied to a rolling 40 equipment. Fig. 2 is a side elevation thereof. Fig. 3 is a section as seen on line 3—3, of Fig. 1. Fig. 4 is an elevation of the valve used in connection with the cage shown in Fig. 3 and to which the stop mechanism is 45 connected. Fig. 5 is a section as seen on line 5—5, of Fig. 1. Fig. 6 is an enlarged side elevation of a portion of the stop mechanism applied to the track. Fig. 7 is a plan view thereof; and Fig. 8 is a detail elevation 50 of the ratchet and pawl connection used on

the device, for retaining the stop mechanism in its effective position until released by manual operation.

In describing my invention, I shall refer to the drawings in which similar reference 55 characters designate corresponding parts throughout the several views and in which 1 indicates a locomotive of the usual or any preferred type having a valve cage 2 thereon which co-operates with the steam pipe 60 and the air pipes for the actuation of the brakes and a valve 3 is arranged in connection with said valve cage. This valve is of the oscillatory type, one end of which is provided with a cylindrical extension 4 and my 65 improved device is designed for direct co-operation with the extension of this valve.

In carrying out the object, I provide an angular or crank arm 5, one member of which is mounted to oscillate in bearings 6 70 suitably mounted on the locomotive. The free end of the last mentioned arm member is designed to form a socket 7 which receives therein the extension 4 of the valve 3 and a set screw 8 is provided in the socket to secure the latter to said valve. The other arm member 5 depends to a plane adjacent the plane of the upper face of the rails and extends in a longitudinal plane outside of the adjacent rail, and the free end of the same 75 is bent angularly and provided with a roller 9. The construction is such that when the arm 5 is in its normal position, the outer depending member thereof is in a vertical position, as shown in Fig. 2 of the drawings, 80 and in this position, the brakes are in their inoperative positions and the steam may, or may not be applied, as desired. When the depending arm member is moved in the direction of the arrow shown in Fig. 2, however, the air brakes will be properly applied 85 and the steam will be simultaneously cut off.

I have provided a means in connection with the track, arranged at predetermined 90 points in the length of the latter, for automatically actuating this crank arm 5. To this end, a pair of shafts 10 and 11 are mounted for oscillation in bearings 12 on the ties 13, at predetermined points in the length of the track, said shafts 10 and 11 100

being spaced one from the other. The ends of these shafts project to points beyond the side of the rails and the one end of each shaft has a drum 14 carried thereon. Cables 15 are arranged in connection with said drums and extend to points (not shown), whereby the same may be actuated by the signal operator and said cables are so wound on the drums as to rotate the one in 10 a direction opposed to the other when said cables are drawn in the same direction.

The shaft 10 carries an arm 16 to oscillate therewith, and the shaft 11 carries a similar arm 17 of considerably less length than the 15 arm 16. The arm 17 is adapted to form a support for the arm 16 so as to dispose the latter upwardly in an inclined position, as shown in Figs. 2 and 6, and in order to permit the arm 17 to be properly engaged 20 with the arm 16, a stop member 18 is provided on the under face of said arm 16. This arm 16 in its normal operative position, is disposed as shown in Figs. 1, 2 and 6 and is arranged in the path of the roller 9 on the 25 lower end of the angular arm 5 which is carried by the locomotive. Thus, as the locomotive moves on the rails, and the arm 16 is in its operative position, the roller 9 is adapted to contact therewith and at such contacting 30 point, a cushioned member 19 is provided, the same being formed of leather or other soft material to absorb the shock. As the locomotive continues in its movement after the 35 roller 9 contacts with the cushioned member on the arm 16, it will be seen that the crank arm will be oscillated in its bearings and the roller 9 moved along the inclined arm 16. The oscillation of the arm 5 in its bearings 40 operates the valve 3, whereby to apply air to the brakes and cut off the steam. It will thus be seen that should the engineer for any reason whatsoever, not observe the signal, the train will be automatically stopped through the provision of this stop mechanism. 45

I have provided for the retention of the stop mechanism in its effective position, until such time as manually released and, to this end, a ratchet 20 is provided on the 50 horizontal section of the crank arm 5 between the bearings 6. Pivoted on a bearing 21, at a point adjacent thereto, is a pawl 22, the outer effective end 23 of which is adapted to engage the teeth of the ratchet 20. A 55 spring 24 coöperates with said pawl and with a portion of the locomotive to normally force said pawl downwardly to its effective position in engagement with the ratchet. The disposition of the teeth on the ratchet 60 and pawl is such as to admit of the crank arm being oscillated in the proper direction to apply the brakes, but the pawl will not admit of said ratchet and crank arm to be returned to its initial position. In order to

65 permit the pawl to be disengaged from the ratchet, a handle member 25 is provided thereon and after the crank arm has been oscillated to the position for actuating the brakes, said pawl is disengaged by raising the same through the medium of the handle 70 member.

As will be seen from the above description and the drawings, the arms 16 and 17 carried on the shafts 10 and 11, are capable of actuation through the medium of the cables 75 which are in control of the signal operator. Should it be desired to dispose these arms to their inoperative positions, for any reason whatsoever, it is only necessary to draw upon the cables 15, which obviously oscillates the shafts 10 and 11 in opposite directions and correspondingly lowers said arms 16 and 17.

From the foregoing description of the construction of my improved device, the operation 85 thereof will be readily understood and it will be seen that I have provided an improved stop mechanism which will positively and automatically stop the locomotive when danger is imminent and not observed 90 by or known to the engineer. It will also be seen that the device is one which is simple and durable in construction, inexpensive to manufacture and one which will be very efficient and useful in operation. 95

While I have particularly described the elements best adapted to perform the functions set forth, it is obvious that various changes in form, proportion and in the minor details of construction may be 100 resorted to without departing from the spirit or sacrificing any of the principles of the invention.

As shown in the drawings, the steam pipes leading from the valve cage 2, are indicated 105 as 26. An air tank 27 is provided, having a pipe 28 leading therefrom, directly to the valve cage and an additional air pipe 29 leads from the valve cage to the brakes.

Having thus described this invention, what 110 I claim is:—

1. In an automatic stop for railways, the combination with a track-way; of a pair of shafts extending transversely thereacross below the rails and mounted for oscillation with respect thereto, an arm carried on one end of each of said shafts, the one arm being of less length than the other and adapted to support the latter in an inclined position, and means for oscillating said shafts simultaneously in opposite directions. 115

2. In an automatic stop mechanism for railways, the combination with a track-way; of a pair of shafts mounted for oscillation below the rails of said track-way and projecting beyond the sides thereof, a drum mounted on one end of each shaft, a cable 120 arranged in connection with said drums to

oscillate the shafts in opposite directions as
said cable is drawn, and an arm mounted
on the opposite end of each of said shafts,
and the arm of one shaft being of less length
5 than the arm of the other shaft and adapted
to support the latter in an inclined position.

In testimony whereof I hereunto affix my
signature in the presence of two witnesses.

BUANAFEDA MONTERASTELLI.
